UNITED STATES PATENT OFFICE

142,054

DESIGN FOR A DUPLEX SOCKET WRENCH

Matthew Lyle Young, Huntington Park, Calif.

Application January 22, 1945, Serial No. 117,530

Term of patent 14 years

(Cl. D54—16)

To all whom it may concern:

Be it known that I, Matthew Lyle Young, a citizen of the United States of America, residing at Huntington Park, in the county of Los Angeles and State of California, have invented a new, original, and ornamental Design for Duplex Socket Wrenches, of which the following is a specification, reference being had to the accompanying drawing, forming a part thereof.

Fig. 1 is a side elevational view of a duplex socket wrench showing my new design.

Fig. 2 is a front elevational view.

Fig. 3 is a rear elevational view.

I claim:

The ornamental design for a duplex socket wrench, substantially as shown.

MATTHEW LYLE YOUNG.
